(57) **CLAIM**

The ornamental design for a cantilevered shelving system, as shown and described.

DESCRIPTION

FIG. 1 is a perspective view of a cantilevered shelving system, showing my new design;

FIG. 2 is a front elevational view thereof;

FIG. 3 is a rear elevational view thereof;

FIG. 4 is a left side elevational view thereof, the right side elevational view being a mirror image;

FIG. 5 is a top plan view thereof; and,

FIG. 6 is a bottom plan view thereof.

The broken line showing on FIGS. 1-2, 4 and 6 is for illustrative purposes only and forms no part of the claimed design.

1 Claim, 5 Drawing Sheets

FIG. 1

FIG. 5**FIG. 6**

UNITED STATES PATENT AND TRADEMARK OFFICE
CERTIFICATE OF CORRECTION

PATENT NO. : Des. 462,541 S
DATED : September 10, 2002
INVENTOR(S) : Robert J. Welch

Page 1 of 1

It is certified that error appears in the above-identified patent and that said Letters Patent is hereby corrected as shown below:

Title page,

Item [57], **DESCRIPTION**,

Line 9, "showing on FIGS. 1-2," should read -- shown in FIGS. 1,2, --.

Item [*], after, "(73) Assignee: **Metro Industries, Inc.**, Reno, NV (US)", insert
-- (*) Notice: This patent issued on a continued prosecution application filed under
37 CFR 1.53(d), and is subject to the twenty year patent term
provisions of 35 U.S.C. 154(a)(2). --.

Signed and Sealed this

Ninth Day of September, 2003

JAMES E. ROGAN
Director of the United States Patent and Trademark Office
